MOTORIZED MOUNT FOR CHEMICAL MORTARS

Ralph H. Tate, Edgewood Arsenal, Md.

Application September 7, 1937, Serial No. 162,723

5 Claims. (Cl. 89—40)

(Granted under the act of March 3, 1883, as amended April 30, 1923; 370 O. G. 757)

The invention described herein may be manufactured and used by or for the Government for governmental purposes, without the payment to applicant of any royalty thereon.

5 This invention relates to a motorized mount for chemical mortars. The chemical mortar is a relatively light, portable weapon which was developed during the World War for use in the trenches. The mortar is placed in an inclined position and is fired by dropping the shell into the muzzle, the powder charge being fired when the shell hits a firing pin in the base of the mortar. The shells are generally filled with chemical warfare agents, such as smoke or fume-generating chemicals.

One important advantage of the chemical mortar is its ready mobility, since it may be easily disassembled and carried to a new emplacement by soldiers. Due to the modern mechanization of 20 armed forces, it is desirable that this weapon be mounted on a motor vehicle for rapid transport, and so arranged that it can be rapidly placed in firing position.

The principal object of this invention is to provide 25 a mount for chemical mortars which may be attached to a motor or other vehicle for rapid transportation, the mount being arranged for ready emplacement on the ground.

A further object of this invention is to provide 30 a mount of the above indicated character which may be quickly emplaced on the ground for firing in stable position on any type of terrain, and which is rapidly seated in firm position so that accurate firing may be obtained without material adjustments.

These and various other objects will be apparent from the following description and appended claims, with the understanding that the invention is not limited to the detailed construction 40 of the embodiment herein described and illustrated.

In the drawings

Fig. 1 is a side elevation of the vehicle with the mortar mount in firing position.

45 Fig. 2 is a plan of the vehicle with the mortar in running position.

Fig. 3 is an enlarged perspective of the mount in firing position.

Fig. 4 is a plan of the stationary and movable 50 frame members with parts broken away.

Fig. 5 is a section on line 5—5 of Fig. 4.

Fig. 6 is an end elevation thereof.

Referring to the drawings wherein like reference characters indicate like parts, Figs. 1 and 2 55 show the mount in its relation to the vehicle.

The vehicle may be of any type and no invention is claimed as regards the usual parts thereof such as the engine, steering mechanism, wheels and axles, and other standard parts. However, the rear portion of the body is of special design. 5

An automotive vehicle is illustrated which has a low over-all height in order to avoid easy spotting by the enemy. The vehicle has the body 1, front and rear wheels 2 and 3, and the usual internal combustion engine. The rear portion of the vehicle is provided with two channel-shaped runways 5 having their open sides facing inwardly for slidably receiving the carriage frame and mortar support mechanism designated generally by numeral 6. The mortar is never fired from its carried position on the vehicle but is dropped over the rear of the vehicle to rest on the ground, and is fired at an elevated angle over the vehicle, as seen in Fig. 1.

The mortar barrel 7 is supported at its lower end on a base plate 8 which rests on the ground during firing. The upper portion of mortar 7 is supported in a cradle connected to carriage frame 6 by an elevating screw 9, the lower end of the screw being supported by and adjustable 25 transversely of frame 6. A pair of heavy springs 11 are connected to the base plate 8 by chains 12 and to the frame of the vehicle.

On opposite sides of the vehicle adjacent the rear end are boxes 13 in which are carried the shells for the mortar, these boxes having doors which swing outwardly. As seen from Fig. 2, the frame 6 is slidable between and beneath the shell boxes 13 for transport of the mortar. 30

Referring to Figs. 4, 5, and 6, the slidable carriage frame 6 includes two side members 15 preferably of channel iron connected together by cross pieces 16, 17, and 18, bolted or welded to side members 15. The width of frame 6 is such that it is slidable within the channel members 40 5 of the vehicle. Channels 5 are slidable within channels 15 on the vehicle and carry four sets of anti-friction rollers 19, one roller of each set bearing against the upper rim of channel 5 and one against the lower rim. Angle irons 21 are secured to cross members 16, 17, and 18, and provide a bearing for rotatable traversing screw 22 which is rotated by wheel 23.

Adjacent the front end of frame 6 are two bracing members 24 which are secured to cross member 16 and 17. Members 24 support a saddle member 25 in which the barrel of the mortar rests during transport as seen in Fig. 1 suitable straps 26 being used to prevent movement of the barrel. 55

The stationary frame 5 has a latch 27 operable by handle 28, this latch engaging cross member 16 to retain slide 6 in the forward position. Pivoted to the two stationary channels 5 near the rear of the vehicle are two spring pressed latches 29 which engage cross member 17 on the slide to prevent the slide from moving forward during firing. These latches may be released by handles 31.

Secured to the upper faces of stationary channels 5 near the rear are hooks 32 positioned in pockets formed by angular plates 33, as seen in Figs. 4 and 5. The base plate 8 has angles 34 projecting outwardly from the forward corners which are adapted to engage hooks 32 when the weapon is being transported, as seen in Fig. 1, the baseplate being supported in vertical position.

Baseplate 8 comprises a rectangular plate having spades on the lower surface to dig into the earth and hold the plate against movement after an initial round of firing. On the upper surface of baseplate 8 is a pivotal connection 35 for barrel 7, and hand bars 36 along two sides to facilitate handling of the weapon.

The mortar barrel 7 is supported at its center by a cradle 37 which is connected to a traversing and elevating mechanism. The elevating and traversing mechanism includes a clevis 38 which may be readily attached to cradle 37 by a removable pin. Clevis 38 is secured to the end of elevating screw 9 which extends into and through the support 39. Hand wheel 41 is rotatably connected to support 39 and has a corresponding threaded opening engaging the threads on screw 35 9, whereby rotation of the hand wheel will raise or lower the cradle 37 and mortar barrel 7.

Support 39 has a portion which is threaded on traversing screw 22 of the carriage frame 6. By rotating wheel 23, traversing screw 22 may be rotated to thus move support 39 and barrel 7 transversely, a mil scale (not shown) serving to indicate the degree of movement.

Operation.—During transport the weapon is loaded as shown in Fig. 2, with the slidable frame 6 moved forward and held by catch 27, Fig. 5.

Wings 34 on baseplate 8 are caught in hooks 32 and the barrel 7 rests in cradle 37 and is retained by strap 26. When in firing position the latch 27 is released by raising handle 28, the baseplate is grasped by bars 36, and the baseplate 50 is rotated to a horizontal position and lowered to the ground. The parts are then in the position shown in Fig. 3.

When the frame 6 slides to the rear, the rollers 19 rotate within the stationary channels 5. When 55 the frame is at the rear position, catches 29 automatically engage cross member 17 to hold the assembly in position. The barrel may be raised or lowered by hand wheel 41 or traversed by wheel 23. Channels 5 have end closure plates 60 42, Figs. 3 and 5, to prevent slide 6 becoming disengaged.

The shells are readily accessible in compartments 13. During firing the baseplate seats itself in the ground and chains 12 and springs 11 prevent

further backward movement, springs 11 preventing shocks being transmitted to the vehicle frame. The mortar may be rapidly replaced in the vehicle for transport.

While I have shown and described the preferred embodiment of this invention, I wish it to be understood that I do not confine myself to the precise details of construction herein set forth by way of illustration, as it is apparent that many changes and variations may be made therein by those skilled in the art, without departing from the spirit of the invention or exceeding the scope of the appended claims.

I claim:

1. A mobile mount for a chemical mortar comprising a wheeled vehicle having a stationary frame including longitudinal guide rails, a slid- 15 able frame movable longitudinally on said rails, said slidable frame having a threaded traversing screw mounted in bearings, a traversing block 20 threaded on said screw, an elevating screw passing through said block, means on said block to raise and lower said elevating screw, a mortar barrel having its upper portion supported by said elevating screw, a baseplate connected to the 25 lower end of said barrel, said elevating screw and barrel and baseplate being rotatable about said traversing screw from a horizontal traveling position to a firing position with the baseplate on the ground, and a hand wheel for rotating said trav- 30 ersing screw.

2. A mobile mount for a chemical mortar comprising a wheeled vehicle, a substantially rectangular rigid frame slidable longitudinally in the vehicle, a threaded traversing screw supported 35 transversely of and adjacent the rear of said frame, a traversing block threaded on said screw and movable across the frame by rotation of said screw, an elevating screw passing through said block perpendicular to said traversing screw, means on said block to raise and lower said elevating screw, a chemical mortar barrel secured to the upper end of said elevating screw, and a baseplate directly pivoted to the lower end of said barrel and adapted to transmit the recoil of the barrel to the ground when the mortar is fired, whereby the mortar may be pivoted about the traversing screw as a center from a horizontal transporting position to an elevated firing position with the baseplate resting on the ground and the traversing screw supporting the barrel 40 for firing over the vehicle.

3. The invention as defined in claim 2 wherein latches are provided on the vehicle which engage the slidable frame when in its firing position to prevent forward movement thereof.

4. The invention as defined in claim 2 wherein the slidable frame supports an upstanding semi-circular cradle upon which the mortar barrel rests during transport.

5. The invention as defined in claim 2 wherein two spring members connect the baseplate and the stationary portion of the vehicle.

RALPH H. TATE.
